UNITED STATES PATENT OFFICE.

GEORGE W. YOUNG, OF GLENDALE, CALIFORNIA.

AIR-BRAKE AND MEANS TO START AUTOMOBILES.

No. 827,839.

Specification of Letters Patent.

Patented Aug. 7, 1906.

Application filed January 23, 1903. Serial No. 297,456.

To all whom it may concern:

Be it known that I, GEORGE W. YOUNG, a citizen of the United States, residing at Glendale, in the county of Los Angeles and State 5 of California, have invented new and useful Improvements in Air-Brakes and Means to Start Automobiles, of which the following is a specification.

The object of my invention is to provide an 10 autocar with means to brake and start the car with air, utilizing the motion lost in stopping the car to start it. I accomplish these 15 objects by means of the device described herein and shown in the accompanying drawing, which is a diagrammatic view of the running-gear of an autocar with my braking and starting device in place thereon.

Upon the frame A of the car is transversely mounted a compression air-cylinder B. Connected therewith are the ports C and D, leading into the air-pumps E and F, in the cylinders of which are mounted the pistons G and H, adapted to reciprocate therein. The said pistons are workably connected with the 25 crank-shaft I, carrying in the center thereof the sprocket-wheel J. A sprocket-chain K extends around and over the sprocket-wheel J and the sprocket-wheel L, rigidly affixed to the clutch M. This clutch is mounted co- 30 axially with the hind axle and is thrown into or out of engagement with the clutch-drum N, keyed to one member of the hind axle, by means of the clutch-operating yoke O. This clutch is operatively connected with the 35 hand-lever P, which projects upwardly in close proximity to the seat of the driver. Leading from the compression-cylinder is the port Q, which communicates with the starting-cylinder R, the opening through said port 40 being controlled by the cut-off valve S. Slidably mounted in the starting-cylinder is the piston T, the rod U, upon which the same is mounted, carrying on its upper side the rack V. This rod projects forwardly under the 45 main driving-shaft W and brings the teeth of the rack in engagement with the spur-gear X, revolvably mounted on the driving-shaft and connected therewith by the ratchet k, permitting the rotation of the spur-gear loosely in 50 one direction and preventing its rotation on the shaft in the other direction. In the head of the starting-cylinder I have provided a stop-cock Y, adapted to be opened and closed by the lever Z.

55 My device is operated as follows: The car being in motion and it becomes desirable to

stop or brake the same, the hand-lever P is thrown forward. This will throw the clutch M into engagement with the clutch-drum N and cause the sprocket-wheel to rotate, carrying therewith the sprocket-chain K, which will impart motion to the crank-shaft I and cause the air-pumps E and F to pump air into the compression-cylinder B. As the air becomes compressed in said cylinder it will 60 operate to brake the car as the pressure in the tank is increased until the car is brought to a full stop, at which time there will be a great pressure of air in the compression-cylinder. The amount of pressure therein will be shown 65 by the pressure-gage a, disposed on the dash of the car or elsewhere where easily seen by the driver. Now when it is desired to start the engine, the pressure of air in the compression-tank is utilized for that purpose in this 70 way: The hand-lever b is thrown backwardly, carrying therewith the levers Z and c, which operate to close the valve Y and open the valve S, permitting the air to enter freely through the port Q into the starting-chamber 75 R and carrying forwardly the piston T. This will impart motion to the driving-shaft W, upon which the fly-wheel d is mounted. When the piston T has advanced sufficiently forward to contact with the inwardly-projecting 80 end of the cut-off rod e, the cut-off rod operatively connected with the levers Z and c will cause the same to move forwardly and open the valve Y and at the same time close the valve S, thereby removing the pressure from 85 the piston T and cutting off the discharge of air from the compression-chamber. Spring T' assists in returning the piston to its normal position.

When necessary to remove the air-pressure 90 from the compression-tank, the hand-lever f, connected with the bell-crank lever f', connected in turn with the bell-crank lever g, is adapted to work the cut-off valve h and open or close the said valve, controlling the port 95 leading from the compression-cylinder into the open air. A horn may be connected at this or the other end of the compression-chamber and sounded when desired by the operation of the hand-lever placed for that 100 purpose, or connection may be made therewith to inflate the pneumatic tires on the car.

Having described my invention, what I claim as new, and desire to secure by Letters Patent, is—

1. A combined air-brake and vehicle-starter comprising a compression-cylinder

and an air-chamber in the form of a dash-pot in communication with said cylinder in which air is temporarily compressed by a moving part of the machine in the act of braking previous to its admission into the compression-cylinder.

2. In a vehicle, the combination with a compression-cylinder, of a pump-cylinder in communication therewith, a valve for controlling the passage from the pump-cylinder into the compression-cylinder, a piston in the pump-cylinder, and means for communicating motion to the piston from a moving part of the vehicle whereby to temporarily utilize the air in the pump-cylinder to retard and cushion the piston whereby to act as a brake upon the vehicle, after which the air exhausted from said pump-cylinder is stored in the compression-cylinder.
- 15 3. In a vehicle, the combination of a compression-cylinder, of a pump-cylinder in communication therewith, a valve for controlling the passage from the pump-cylinder into the compression-cylinder, a piston in the pump-cylinder, and means for communicating motion to the piston from a moving part of the vehicle whereby to temporarily utilize the air in the pump-cylinder to retard and cushion the piston whereby to act as a brake upon the vehicle, after which the air exhausted from said pump-cylinder is stored in the compression-cylinder, a storing-cylinder, a pipe connecting the storing and compression cylinders and a valve for controlling the passage 35 of air from the compression-cylinder to the storing-cylinder.
4. In an automobile means to start the engine comprising a compression-tank for the reception of air under pressure and means to fill the tank with air at will, a starting-cylinder connected with the compression-tank and provided with a cut-off valve adapted to permit the air to pass from the compression-tank to the starting-cylinder, a discharge-port in the starting-cylinder having a controlling-valve therein and means to operate said valve, a piston in the starting-cylinder having a piston-rod connected therewith having upon its upper edge a rack, the said rod ex-

tending outwardly over the driving-shaft, a spur-gear loosely mounted on the driving-shaft in combination with a ratchet disposed on said shaft and adapted to permit the rack to rotate freely in one direction and to prevent its rotation in the other direction, a cut-off rod, one end of which projects into the end of the starting-cylinder and connected with the controlling-valve on the discharge-port on the starting-cylinder and also with the cut-off valve on the connection between the compression-tank and the starting-cylinder, the piston adapted in its movement to contact with and move the cut-off rod and thereby operate the cut-off valves.

5. Means to start the engine of an automobile comprising a compression-tank B and a starting-cylinder R, the said cylinder and tank being connected one with the other to permit the air in the compression-tank to pass into the starting-cylinder, a controlling-valve S on the connection between the cylinder and the tank, an operating-lever C on said cut-off valve, a discharge-port on said starting-cylinder having a cut-off valve Y therein, a valve-operating lever Z on said cut-off valve, the controlling-levers e and Z operatively connected with a cut-off rod e, a cut-off rod e projecting into the starting-cylinder and adapted to be operated by the piston in said cylinder, a piston P in said cylinder and having a rod U connected therewith carrying on the upper face thereof a rack V, a spur-gear X loosely mounted on the driving-shaft W, the said spur-gear being workably connected with the ratchet k, a ratchet k on the driving-shaft adapted to permit the spur-gear to move freely in one direction and to prevent its rotation in the reverse direction and means to permit the air to pass from the compression-tank into the starting-cylinder substantially as herein shown and described.

In witness that I claim the foregoing I have hereunto subscribed my name this 12th day of January, 1906.

GEORGE W. YOUNG.
